CLAIM

The ornamental design for an illumination device, as shown and described.

DESCRIPTION

FIG. 1 is a perspective view of an illumination device showing our new design.

FIG. 2 is a front elevational view of FIG. 1.

FIG. 3 is a rear elevational view of FIG. 1.

FIG. 4 is a left-side, elevational view of FIG. 1.

FIG. 5 is a right-side, elevational view of FIG. 1.

FIG. 6 is a top plan view of FIG. 1; and,

FIG. 7 is a bottom plan view of FIG. 1.

The broken lines are for illustrative purpose only and they form no part of the claimed design.
